UNITED STATES PATENT OFFICE.

ISAAC N. GIFFIN, OF WINTERHAVEN, FLORIDA.

VICE.

1,212,136.

Specification of Letters Patent.

Patented Jan. 9, 1917.

Application filed February 25, 1916. Serial No. 80,450.

To all whom it may concern:

Be it known that I, ISAAC N. GIFFIN, a citizen of the United States, residing at Winterhaven, in the county of Polk and State of Florida, have invented certain new and useful Improvements in Vises, of which the following is a specification.

This invention contemplates an improved vise especially adapted for use by carpenters, and has as its primary object to provide a device of this character which may be attached to a carpenter's bench and which may be easily and quickly operated to either clamp or free the work.

The invention has as a further object to provide a vise wherein the use of the ordinary clamping screw will be eliminated and wherein the space between the clamping jaw of the vise and the member coacting therewith will be unobstructed to receive the work. And the invention has as a still further object to provide an easy and effective means for adjusting the vise to accommodate various sizes of work and wherein the clamping jaw of the vise will be yieldably urged to a position for receiving the work.

Other and incidental objects will appear as the description proceeds and in the drawings wherein I have illustrated the preferred embodiment of the invention and wherein similar reference characters designate corresponding parts throughout the several views, Figure 1 is a fragmentary perspective view showing my improved device applied to a conventional type of work bench, Fig. 2 is a sectional view more particularly showing the construction and mounting of the several elements of the device, Fig. 3 is a fragmentary detail sectional view more particularly showing the mounting of the clamping jaw of the device, and Fig. 4 is a detail perspective view of the cam lever employed.

In order that the mounting and operation of my improved device may be clearly brought out, I have, in the drawings, illustrated my improved vise in connection with a conventional type of work bench 10 which is provided with a side member 11 and is supported in the usual manner, by a plurality of legs one of which is designated 12. While I have indicated that my improved vise is particularly adapted for carpenters' use and have illustrated the vise in connection with a carpenters' work-bench, still, it will be seen as the description of the inven-

tion progresses, that the vise is equally applicable for use in other adaptations and I do not, therefore, wish to limit myself in this regard, as my improved vise is adapted for attachment to any suitable character of support other than a work-bench, the said bench will be designated as a support, since, as will presently appear, such bench in reality, supports the vise and in using the word support, I will not, therefore be limited to a work-bench or any other particular character of support.

Coming now more particularly to the subject of the present invention, I employ a clamping jaw or member 13 which is in the nature of a straight bar and may be formed of wood or other suitable material. Pivotally supporting the clamping jaw 13 adjacent its lower extremity, is a bolt or other suitable fastening device 14 which extends freely through the said jaw and is detachably connected to the leg 12 of the work-bench 10. Preferably interposed between the lower extremity of the jaw 13 and the said leg of the work-bench is a spacing block or washer 15 which surrounds the bolt 14. The jaw 13 is adapted to coact with the side member 11 of the work-bench in receiving the work and particular attention is now directed to the fact that since the said jaw is loosely mounted upon the bolt 14, it may pivot thereon in a plane at right angles to the axis of the bolt to seat flatly against the adjacent side of the work. By this arrangement, the clamping jaw may accommodate itself to work of uneven contour.

Associated with the clamping jaw 13 is a rock arm or lever 16 which may also be formed of wood or other suitable material. The arm 16 is in the nature of a straight bar and is pivotally supported at a point intermediate its ends by a pin 17 to extend at substantially right angles to the jaw 13. The pin 17 is arranged to extend freely through the side member 11 of the work-bench 10 and is screw threaded adjacent its inner extremity to adjustably and detachably engage an anchoring member or plate 18 mounted upon the inner side of the said member 11. The anchoring member 18 is preferably formed of metal as is also the pin 17 and may be connected to the side member 11 by screws or other suitable fastening devices as illustrated in the drawings. Interposed between the plate 18 and the rock arm 16, is a helical spring 19 which sur-

rounds the pivot pin 17 and preferably, the said pin at its outer extremity is provided with a loop or other suitable type of handle 20 whereby the pin may be easily adjusted upon the plate.

At its inner extremity, the rock arm 16 is preferably cut away to receive the clamping jaw 13 and is pivotally connected to the said jaw adjacent the upper extremity thereof, by a bolt or other suitable fastening device 21, which extends through the said jaw and freely through the rock arm as particularly shown in Fig. 2 of the drawings. In this connection, it is pointed out that the rock arm 16 is provided with slots elongated longitudinally of the said arm to freely receive the pin 17 and the bolt 21 respectively so as to compensate for the rocking movement of the jaw 13 when transversely shifted into angular relation to the member 11 to engage a piece of work of uneven contour.

Mounted upon the outer extremity of the rock arm 16 is a cam lever 22, shown in detail in Fig. 4 of the drawings. The lever 22 is extended through the adjacent terminal of the said arm and is swingingly connected thereto while the arm is provided with a longitudinally extending slot 23 which freely receives a cam 24 carried by the said lever. Arranged to coöperate with the cam is a wear plate 25 suitably connected to the side member 11 of the work-bench.

It will now be seen that the spring 19 will act to yieldably urge the jaw 13 away from the work-bench 10 and will normally hold the said jaw in spaced relation to the work bench for receiving the work. The jaw 13 may be easily and quickly adjusted relative to the work-bench for receiving work of various sizes, by simply turning the pin 17 by means of its handle 20 which may be readily grasped for this purpose. When the cam lever 22 is disposed in the position shown in Fig. 1 of the drawings, the work 45 may be positioned between the jaw 13 and the bench 10. To clamp the work, the cam lever is then swung to the position shown in dotted lines in Fig. 2 of the drawings, causing the arm 16 to rock upon the pivot pin 17 for urging the jaw 13 toward the work to tightly clamp the work in place and of course, the jaw 13 may be released with equal facility by simply returning the cam lever 22 to its normal position when the spring 19 will act to move the said jaw away from the work. It will therefore be seen that I provide an arrangement wherein the jaw 13 may be easily and quickly operated to either clamp or release the work 60 and as previously brought out, the said jaw is so mounted that, under ordinary circumstances, it will seat flatly against the work to securely engage therewith. Moreover, it is to be observed that the use of an ordinary clamping screw is eliminated and ac-

cordingly, the space between the jaw 13 and the work-bench 10 is unobstructed so that work may be easily positioned between the said jaw and the bench 10. If desired, the side member 11 of the said bench may be 70 provided with spaced removable pegs 26 adapted to support the work in position to be clamped.

Having thus described my invention, what I claim and desire to secure by Letters Patent is:

1. A device of the character described including a pivoted clamping jaw, a rock arm operatively engaging with the said jaw with its free extremity extending laterally from one side of the jaw, and means associated with the free extremity of said rock arm and operable to shift the arm for urging said jaw to active position.

2. A device of the character described including a pivoted clamping jaw, an adjustably mounted rock arm operatively connected to said jaw with its free extremity extending laterally therefrom, and means associated with the free extremity of said rock arm and operable to shift the arm for urging the said jaw to active position.

3. A device of the character described including a support, a pivoted clamping jaw associated therewith, a rock arm pivotally connected to said jaw, a pivot pin adjustably supporting the jaw with respect to the support, means carried by said pin and acting upon the said arm for normally urging the said jaw away from the support, and means associated with the said arm for urging the jaw toward the support.

4. A device of the character described including a support, a clamping jaw associated therewith, a rock arm operatively connected to the said jaw to extend laterally therefrom, means pivotally supporting the said arm and adjustable for spacing the jaw either toward or away from the support, and means associated with the free extremity of the said arm for urging the jaw toward the support to coact therewith.

5. A device of the character described including a support, a clamping jaw associated therewith, a rock arm operatively connected to said jaw, means pivotally supporting said arm, yieldable means associated with the said first mentioned means and acting upon the arm for normally urging the jaw away from the support, and means operatively connected to the free extremity of said arm for urging the jaw toward the support to coact therewith.

6. A device of the character described including a support, a clamping jaw freely connected thereto, a rock arm freely connected to the said jaw to extend laterally therefrom, a pivot pin freely engaging the said rock arm and adjustable upon the support for spacing the jaw either toward or 130

away from the support, a spring carried by the said pin and acting upon the arm for normally urging the jaw away from the support, and a cam lever carried by the free 5 extremity of said arm and shiftable to coact with the support for urging the said jaw toward the support to coact therewith.

7. The combination with a work bench, of a clamping jaw pivotally connected to the 10 bench with its free extremity arranged to

coact therewith, a rock arm operatively engaging the said jaw to extend laterally therefrom and pivotally supported upon the bench, and means coöperating with the free end of said arm and with the bench for 15 rocking the arm to shift the said jaw toward the bench to active position.

In testimony whereof I affix my signature.

ISAAC N. GIFFIN. [L.S.]
